UNITED STATES PATENT OFFICE.

SAMUEL E. SPERRY, OF WOODHAVEN, NEW YORK, ASSIGNOR TO INTERTYPE CORPORATION, OF NEW YORK, N. Y., A CORPORATION OF NEW YORK.

CHANNEL-ENTRANCE FOR TYPOGRAPHIC MACHINES.

1,245,055.

Specification of Letters Patent. Patented Oct. 30, 1917.

Application filed September 27, 1916. Serial No. 122,451.

To all whom it may concern:

Be it known that I, SAMUEL E. SPERRY, a citizen of the United States, residing at Woodhaven, in the county of Queens and 5 State of New York, have invented new and useful Improvements in Channel-Entrances for Typographic Machines, of which the following is a specification.

The present invention relates to improvements in typographical machines, and more especially, to those of the linotype class, as shown and described in the patent to Ottmar Mergenthaler, No. 436,532, granted September 16, 1890. In machines of that type, type 10 bars or slugs are cast from lines of matrices which are stored in a matrix magazine and delivered therefrom under the control of a keyboard manipulated by the operator, the matrices, after a cast has been made therefrom, being returned to their respective 15 channels or compartments of the magazine by distributing mechanism.

The present invention is more particularly applicable to a machine of the class mentioned which embodies two or more matrix magazines, any one of which may be brought to an operative position relatively to the matrix delivery and distributing mechanisms. A plural magazine machine of such 20 type is shown and described in prior application of Thomas S. Homans, Serial No. 833,738, filed April 22, 1914, the present invention being intended particularly as an improvement upon the machine shown in 25 that application. In machines of this type, and as shown in the Homans application referred to, a multiple chute known as a channel entrance is provided between the distributor and the matrix-receiving end of the 30 magazine, this channel entrance serving to properly guide and direct the matrices from the distributor into the appropriate channels or compartments of the magazine.

Experience has shown that because of 35 discrepancies in workmanship, slight springing of the framework of the machine, or other causes, the channel entrance at times will be slightly out of register with the operative magazine, this being particularly likely to 40 occur where the machine embodies two or more magazines with means for bringing any one of the magazines into operative position.

The primary object of the present invention is to provide an improved channel entrance which will be self-registering with re-

lation to the magazine in operative position, thus avoiding difficulties heretofore experienced due to lack of registration between the channel entrance and the magazine, especially where plural magazines are employed 60 in the machine.

Another object of the invention is to provide an improved partition or guide for the channel entrance whereby the spaces or channels of the entrances will be more suitably proportioned in relation to the thicknesses of the matrices, the matrices will be guided more accurately as they enter the magazine and yet ample space will be provided at the top of the entrance channel to 65 permit the matrices to fall into the respective spaces of the entrance from the distributor.

To these and other ends the invention consists in certain improvements and combinations and arrangements of parts, all as will be hereinafter more fully described, the features of novelty being pointed out particularly in the claims.

In the accompanying drawings—

Figure 1 represents a side elevation, partly in section, of the upper portion of a typographical machine of the linotype class embodying the present invention, the channel entrance being shown in operative position 80 by the full lines and in inoperative position by the dotted lines;

Fig. 2 represents a vertical section through the upper portion of a magazine and the adjacent parts of the machine, showing the 85 channel entrance as viewed from the front;

Fig. 3 represents, on an enlarged scale, a vertical section through the channel entrance;

Fig. 4 is a diagrammatic view illustrating 90 the passage of a matrix from the channel entrance and into the magazine;

Fig. 5 is a detail perspective view of one of the partitions of the channel entrance and

Fig. 6 is a detail view of portions of the 100 channel entrance and its carrying frame showing the manner in which the channel entrance is supported by the carrying frame while the channel entrance is out of operative relation with the magazine.

Similar parts are designated by the same reference characters in the several views.

The present invention is applicable generally to typographical machines employing circulating matrices. It is particularly ap- 110

2

5 plicable to machines of the linotype class and more especially to machines of this class embodying a plurality of magazines and means for bringing the different magazines into operative position. The preferred embodiment of the invention is shown in the accompanying drawing and will be herein-after described in detail, this embodiment of the invention being especially applicable 10 to a machine constructed as shown and described in the Homans application referred to. It is to be understood, however, that the invention is not restricted to the particular construction shown, nor is it limited 15 in its application to machines of the types referred to, as other uses may be found for the invention and constructions equivalent to that shown may be used, all of which will be included within the present invention 20 and within the scope of the claims.

25 In the present instance, 1 designates the upper portion of the main frame of a typographical machine of the linotype class, this frame serving to support the distributor beam 2 to which the distributor rail 3 is attached. The distributor, of which the rail 2 forms a part, may be of the same general construction as that commonly used in machines of the linotype class. As shown, 30 the lower edge of this rail is provided with the usual combination ribs to coöperate with the teeth in the upper recesses of the matrices whereby the matrices will hang upon the lower edge of the rail while they are advanced and they will drop from the rail when they reach positions above their respective channels or compartments in the magazine. Advancement of the matrices along the rail is effected by the distributor 35 feed screws 4. M represents one of the matrices, suspended from the distributor rail or bar. In the present instance, the machine is constructed so as to contain two magazines 5 and 6, either one of which may be 40 brought into operative position, the upper magazine 5 being shown in operative position in Fig. 1. These magazines are supported and positioned by a magazine frame 7 and any suitable means, such, for example, 45 as that shown in the Homans application referred to, may be employed for shifting this frame to bring the desired magazine into operative position where it may deliver matrices by manipulation of the keyboard 50 of the machine, and it may receive matrices 55 returned thereto by the distributor.

60 A suitable number of brackets 8 are attached to the frame 1 and a channel entrance frame 9 is pivoted on these brackets and on the axis 10. To the upper or free end of the frame 9 is pivoted a supplementary channel entrance frame 11, this supplementary frame being pivoted on the axis 12. The supplementary frame carries the channel entrance, and this channel entrance com-

70 prises, preferably, a curved rear plate 13 which is secured to the frame 11, a coöperative front plate 14, and a suitable number of partitions 15 which are fitted between the plates just mentioned. The partitions 15, as shown, are provided at their rear edges with pairs of lugs 16 which project through openings 17 in the plate 13, and these lugs have hook-shaped portions to lock upon an edge of the opening 17. A bar 75 18 in rear of the plate 13 is arranged to bear upon the lugs 16 and thereby retain them in locked position, the bar being held in locked position by screws or equivalent devices 19. The front plate 14 of the channel 80 entrance may be held in place by a bar 20 which passes through lugs 21 which project forwardly from the partitions 15 and through openings 22 in the front plate. Suitable spacing of the upper ends of the 85 partitions may be secured by a plate 23 which, as shown, is set in the upper portion of the frame 11 and has notches 24 which coöperate with lugs 25 projecting from the rear edges of the partitions.

90 The forward movement of the frame 9 is limited by set screws 26 which may be mounted in the brackets 8. Set screws 27 are provided for the purpose of supporting the supplementary frame 11 on the frame 9 when the channel entrance is moved to an inoperative position, (this being shown in Fig. 6) the supplementary frame carrying the channel entrance being, however, positioned relatively to the magazine by means 100 independent of these set screws 27. Preferably, and as shown, the channel entrance is provided toward each side thereof with a cam-like finger 28, which, when the channel entrance approaches operative relation with the magazine, rides upon the upper side of the magazine and guides the channel entrance for movement longitudinally of the magazine, and as the channel entrance moves into operative position, these fingers accurately align the matrix spaces of the channel entrance at the proper elevation with respect to the matrix channels in the magazine. It is advantageous to so adjust the set screws 27 and the channel positioning fingers 28 that the frame 11 carrying the channel entrance will be raised off of the set screws 27 when the channel entrance is positioned by the fingers 28, this being shown 110 in Fig. 3. This arrangement not only enables the fingers 28 to accurately position the channel entrance according to variations in the position occupied by the magazine, but it also enables the upper end of the channel entrance to clear any matrices hanging from 115 the distributor bar when the channel entrance is swung into inoperative position preparatory to changing of the magazines, as the channel entrance will be permitted to descend as it moves rearwardly to such an 120 125 130

extent as to require a minimum beveling or cutting away of the forward upper corner of the channel entrance to clear the matrices. Also, it is preferable to locate the axis 10 in substantially the same relation to the distributor and the upper end of the operative magazine as in the Homans application hereinbefore mentioned, as such location of the axis 10 enables clearance of the entrance by the magazines when the latter are shifted.

Any suitable means may be provided for moving the channel entrance to inoperative position, as shown by the dotted lines in Fig. 1, preparatory to a change of magazines, and for returning the channel entrance to operative position after such change has been made. For example, as shown, a lever 29 may be pivoted near the front of the machine within reach of the operator, this lever being connected by a link 30 to the frame 9 at 31. When the channel entrance is in inoperative position, the supplementary frame 11 which directly carries the entrance will be supported on the frame 9 by the set screws 27. While the channel entrance is in inoperative position, it may be further swung to the substantially inverted position, as shown by the dotted lines at the extreme right of Fig. 1, the motion of the channel entrance in such direction being limited, preferably, by a stop 32 on the frame 9.

The present invention also provides an improved partition for the channel entrance which will insure correct passage of the matrices through the entrance and into the magazine. The spaces in the channel entrance between the partitions are proportioned according to the size of the matrices belonging in the corresponding magazine channels, and some of these spaces are commonly made so large that when a font of narrow faced matrices is employed, the matrices falling through the wider spaces of the channel entrance have sufficient room to turn or twist angularly to such an extent that they are likely to enter between the plates of the magazine without engaging the grooves therefor. This difficulty is avoided by employing partitions constructed in accordance with the present invention. As shown in the present instance, each partition 15 has its lower portion offset laterally, as at 33, and a leaf 34 is welded or otherwise fastened to the recessed side of the partition. This leaf is so shaped that it will restrict the matrix space in the channel entrance in proximity to the magazine. For example, as shown, the leaf diverges outwardly as it extends downwardly from the offset 33 of the partition, it reaching its maximum divergence at a point approximately at the upper end of the magazine and then converges 65 toward the partition, it reaching the par-

tition at the lower end thereof. By arranging the lower ends of both the partition and the leaf so that they enter the magazines, it is possible to construct the leaf of very thin material and to bring the ends of the leaf and the partition together, thereby preventing yielding of these parts under the pressure of the falling matrices. 70

I claim:—

1. In a typographical machine embodying a matrix magazine, a matrix distributor therefor, and a channel entrance arranged between the magazine and distributor and movable in a direction longitudinally of the magazine, means coöperative with the magazine for insuring accurate registration of the entrance with the magazine. 75

2. In a typographical machine embodying a matrix magazine, and a matrix distributor therefor, an intermediate channel entrance movable to and from an operative position in a direction longitudinally of the magazine and provided with means to coöperate with the magazine and thereby position the entrance accurately relatively to the magazine. 80

3. In a typographical machine embodying a matrix magazine, a channel entrance therefor movable to and from an operative position relatively thereto and carrying devices to rest upon the upper side of the magazine to guide the channel entrance for movement longitudinally of the magazine and thereby position the entrance relatively thereto. 95

4. In a typographical machine embodying a matrix magazine and a matrix distributor therefor, a channel entrance, means for mounting the same to move to and from an operative position between the magazine and distributor, the channel entrance having means to coöperate with the magazine to support the entrance in register therewith, and means to support the entrance after the latter has been moved out of operative relation with the magazine. 105

5. In a typographical machine of the class embodying a matrix magazine and a matrix distributor, a channel entrance, a swinging frame, and a supplementary frame pivoted on said swinging frame and carrying the entrance, and means normally inoperative but operative after the entrance is moved away from the magazine to support the supplementary frame and the entrance thereon. 115

6. In a typographical machine of the class embodying a matrix magazine and a matrix distributor, a channel entrance, a swinging frame to which said entrance is movably connected and operative to carry the entrance to and from an operative position between the magazine and distributor, and means on the entrance to coöperate with the magazine and thereby guide and hold the entrance in alignment with the magazine. 125

7. In a typographical machine embodying a magazine having matrix channels, a channel entrance comprising a plurality of partitions forming matrix-guiding spaces between them, certain of the partitions being composed of two thicknesses of material spread apart laterally and rejoined at a point within the magazine.

8. In a typographical machine embodying a magazine having matrix channels, a channel entrance comprising a plurality of partitions forming matrix-guiding spaces between them; certain of the partitions being

offset laterally and having a leaf arranged at one side thereof, the leaf being bent laterally away from the partition and then bent to rejoin the partition at a point within the magazine. 15

In testimony whereof I have hereunto set my hand in presence of two subscribing witnesses.
